UNITED STATES PATENT OFFICE.

CHARLES A. COWLES, OF ANSONIA, CONNECTICUT.

WIRE-DRAWING MACHINE.

SPECIFICATION forming part of Letters Patent No. 619,724, dated February 21, 1899.

Application filed February 23, 1897. Serial No. 624,693. (No model.)

To all whom it may concern:

Be it known that I, CHARLES A. COWLES, of Ansonia, county of New Haven, State of Connecticut, have invented a new and useful Improvement in Wire-Drawing Machines, of which the following is a specification, reference being had to the accompanying drawings.

I will describe a machine embodying my improvement and then point out the novel features in claims.

In the accompanying drawings, Figure 1 is a plan or top view of a machine embodying my improvement, certain parts being omitted on one side to reveal parts located on a lower plane. Fig. 2 is an enlarged transverse section taken on the planes indicated by the dotted line xx , Fig. 1. Fig. 3 is a partly-sectional end elevation of parts of the machine, comprising reels upon which the drawn wire is wound, this view being made upon a scale larger than that of Fig. 1, but smaller than that of Fig. 2. Fig. 4 is an enlarged transverse vertical section on the plane of the dotted line yy , Fig. 1. Fig. 5 is an enlarged longitudinal vertical section taken upon the longitudinal plane indicated by the dotted lines zz , Fig. 1. Fig. 6 is an enlarged rear elevation of one of the drawing-die boxes. Fig. 7 is an elevation of a reel for holding drawn wire. Fig. 8 is a side view of a hand-truck for carrying such a reel. Fig. 9 is an enlarged vertical section of a turn-head, the plane of the section being indicated by the dotted line ww in Figs. 1 and 3. Fig. 10 is a detailed view illustrating a modification. Fig. 11 is another detailed view illustrating a modification.

Similar letters of reference designate corresponding parts in all figures.

A designates the frame of the machine. It may be made of iron and of any approved form.

B' B^2 B^3 B^4 B^5 B^6 B^7 designate boxes for holding the drawing-dies. As shown, they are seven in number, but may be more or less numerous at the pleasure of the constructor. These boxes or holders, as here shown, are of rectangular form and are divided into two compartments b' b^2 . The rear compartment b' receives a lubricating and cooling liquid and the forward compartment b^2 accommodates a drawing-die C , which may be of

any suitable form. As here shown, it is made in the form of a rectangular plate, with a tapering hole passing through it from rear to front. In the direction of the length of its 55 drawing-hole it measures less than the compartment b^2 , so that it may have a rearward movement in the compartment. When in use, it is supported by the wire W being drawn. The compartment b^2 being entirely open at 60 the bottom, the tension of the wire holds the die against the forward wall of the compartment b^2 .

It will be seen that in the top of the rear wall of the compartment b' is a groove, that 65 in the wall which separates the two compartments there is a similar groove, and that in the front wall of the compartment b^2 there is also one of such grooves. All of these grooves extend below the plane of the wire while the 70 drawing operation occurs. The lubricating and cooling liquid may flow from the rear compartment b' over into the compartment b^2 around and upon the drawing-die C . Most of it will pass off through the bottom of the 75 compartment b^2 , although some may pass from the front wall of such compartment. I may additionally use a pipe P for discharging the liquid into a hole in each die. Thus all the dirt and other extraneous matter may be 80 washed off and prevented from interfering with the operation of the die.

Each drawing-die box is supported upon a plate b^3 , which, as here shown, is at the rear end pivotally connected by a bolt b^4 to an arm 85 a , extending laterally from the main portion of the frame A . Hence it may move transversely. The upper part of the plate b^3 is provided with a longitudinal dovetailed groove, in which the drawing-die box is engaged, so as to be 90 free to slide lengthwise. At the forward end the groove of each plate b^3 is closed. Obviously the die-box may move rearwardly out of the normal position by sliding along the plate b^3 . The advantage of providing for this 95 rearward movement of the die in its compartment and the rearward movement of the die-box is that when the block has been stopped and is given a slight movement in the reverse direction the loops surrounding the drawing- 100 rollers will be made larger, thereby preventing friction between the wire and drawing-

rollers. It also takes off the strain from the parts that are engaged by the die-holder during the drawing operation.

Under each die-box is a receptacle D, perforated at the bottom. It rests upon the frame A or an appurtenance thereof. When a die is dropped, it falls into the receptacle. In this way dies may accumulate until such time as they are needed, when the receptacle 10 will be lifted out, the liquid within it will run off, and the dies may be picked out.

Intermediate of the die-boxes are drawing-rollers C' C² C³ C⁴ C⁵ C⁶. They are affixed to the outer ends of shaft c, that are journaled 15 in bearings a', attached to the frame A, and provided with bevel gear-wheels c'. The bevel gear-wheels c' engage with bevel gear-wheels c², affixed to a shaft C⁷, which is journaled in bearings a², affixed to the frame A. 20 Any suitable means may be employed for imparting rotary motion to the shaft C⁷—as, for example, gearing engaging with the gear-wheel c³, affixed to said shaft.

It will be observed that the bevel gear-wheels c' c² for the different rollers C' C² C³ C⁴ C⁵ C⁶ are differently proportioned. This is for the purpose of producing such drawing action as will be commensurate for the elongation of the wire produced by the drawing operation.

30 The rollers are of hollow construction to provide for the circulation of the cooling and lubricating liquid. Their construction may best be understood by reference to Figs. 4 and 5. Each has a body portion c⁴ of cylindric 35 form, which is connected by spokes c⁵ with a hub c⁶. As here shown, the shaft c, upon which the body of each roller fits, is reduced in diameter at the outer extremity, so as to receive the hub c⁶. The hub rests against the 40 shoulder formed where the shaft is reduced. The outer extremity of the shaft is screw-threaded and has a nut c⁷ fitted to it. A spline c⁸ engages the shaft and the hub of the roller, so that the two will rotate together.

45 Adjacent to the outer side of the body of each roller is a flange c⁹. This also fits the shaft c. It is clamped between the side of the face portion c⁴ and of the hub c⁶ of the body of the roller on one side and the nut c⁷ 50 on the other side. It has an opening c¹⁰, which is coincident with the spaces between the hubs c⁶ of the roller-body. It also has openings c¹¹, which are outward of the face portion c⁴ of the roller-body.

55 The cooling and lubricating liquid used in the drawing operation may circulate through the body portion of each roller and also through the flange portion and around the wire which embraces the roller.

60 A chamber c¹², constituting a flange, is arranged adjacent to the inner side of each roller. It is hollow throughout and is fitted into a rabbet formed in a plate c¹³, bolts c¹⁴ being used to secure it in place. The plate 65 c¹³ is provided with a hub c¹⁵, that fits upon the shaft c. A lug or lugs c¹⁶, extending from the chamber c¹² to one side of one of the bear-

ings of the shaft c, is fastened to such bearing by a screw c¹⁷ or other suitable means. The outer wall of the chamber c¹² has a circular opening, into which projects a flange c¹⁸, with which the face portion of the body of the roller is provided. There is, however, an annular space left between this flange c¹⁸ and the outer wall of the chamber c¹², so that 70 the cooling and lubricating liquid may pass through. A pipe c¹⁹ supplies the liquid to the chamber c¹², and from the chamber it flows through the annular space just mentioned over the outer surface of the roller-body. It 80 also flows from the chamber c¹² through the space between the spokes c⁵ of the body of the rollers and thence through the opening c¹⁰ into the flange c⁹ and finally out of the latter through the openings c¹¹ over the roller-body and the wire which embraces the same. 85 Over each roller is a hood c²⁰, which may advantageously be made of sheet metal and having an extended portion a²⁰. The hood is designed to prevent any excessive throw of 90 the cooling and lubricating liquid from the rolls and also to deflect the fluid thrown off by the centrifugal force through the extended portion into the die-box. Hence it will normally be in close relation to its roller. It 95 is fitted to slide vertically along guides c²¹, which are attached to the chamber c¹². When in its normal position, it will rest upon blocks c²², but when raised it may be supported by a bolt c²³, bearing upon the top of one of the 100 guides c²¹. As here shown, the bolt c²³ is pivotally connected to one end of a hand-lever c²⁴, which at the other end is combined with a spring c²⁵, acting in such direction as to throw the bolt over the top of the adjacent 105 guide whenever the shield is lifted sufficiently high. To lower it, the lever may be manipulated against the resistance of the spring. A handle c²⁶, arranged upon one side of the shield, facilitates moving it upward. Obviously 110 the hand-levers c²⁴ may all be operated together by a simple connecting contrivance.

The pipes c¹⁹ for the various rollers lead from the pipes c²⁷, that run lengthwise of the series of rollers and drawing-dies. As may 115 be seen by reference to Fig. 2, the pipes c¹⁹ extend downwardly from the lower portions of the pipes c²⁷ and are provided with controlling-cocks c²⁸, by which the flow of the cooling and lubricating liquid may be regulated. In Fig. 1 I have shown a pipe c²⁷ along one side of the machine, but have omitted it from the other side in order that I might better illustrate other parts. The two pipes c²⁷ at their forward ends communicate with a 120 pipe c²⁹. One of the pipes c²⁷ at the other end communicates with a circulating-pump c³⁰. If desired, there may be a circulating-pump c³⁰ for each of the pipes c²⁷.

Below the two series of rollers and drawing-dies is a large tank E, into which the cooling and lubricating liquid flows and from which it is raised again by the circulating-pump c³⁰. 130

At the forward end of the two series of rollers and drawing-dies are reels F for taking up the wire from the block after the completion of the drawing operation. Each reel is 5 adapted to be fitted upon and engaged to rotate with an upright shaft G. By describing the construction of the reel I will describe the means for supporting and rotating it.

Each shaft G has its upper portion reduced 10 in size, so as to form a shoulder g, upon which rests a reel holder or block F'. This block is adapted to interlock with a reel, and it surrounds the upper portion of the shaft G, being engaged therewith to rotate simultaneously. The bearings g' support the shafts G. Below these bearings the shafts G have gear-wheels g² loosely mounted upon them, and to these gear-wheels are affixed the upper portions g³ of clutches G'. This part g³ of the 15 clutch rests upon the hub of the part g⁴ of the clutch, the latter being fastened rigidly to the shaft. Below the part g⁴ of the clutch is a cone g⁵, which rotates with the shaft G, but is capable of being moved up and down there- 20 on by means of a lever g⁶. When moved upwardly, it swings sidewise an arm g⁷, that is carried by the part g³ of the clutch. By shifting this arm sidewise it produces an engagement between the two parts g³ and g⁴ of the 25 clutch. This constitutes a device for operating the block, whereby the block may be started with a graduated movement. As this clutch of itself forms no part of my invention, it will not be necessary to describe it further 30 than to add that the sidewise movement of the arm g⁷ draws together or permits the separation of the ends of a divided ring, which is attached to the upper part g³ of the clutch for the purpose of engaging or disengaging the 35 said ring and the part g⁴ of the clutch.

The lever g⁶ is fulcrumed to a bracket g¹⁷ and, as here shown, is provided with a foot-piece g⁸, so that it may be operated by the 40 foot of the attendant, a pivoted catch g⁹ being preferably used for the purpose of engaging the foot-piece when it is desired to occupy one position for any length of time—as, for instance, during the drawing operation—while filling any reel F. This constitutes a 45 means for throwing into and out of action the device which may be employed for starting the block with a graduated movement and for doing this without stopping the driving-shaft.

I have shown the lever g⁶ as provided with 50 an arm extending upwardly and provided with a handle g¹⁰. After the filling of any reel the operator disengages the catch g⁹ from the lever g⁶ by means of his foot and then with 55 his hand presses the lever forward, so as to lower the cone g⁵. Thus the disengagement of the shaft G with the gear-wheel g² will be effected. If, as here shown, the upper part 60 of the lever g⁶ shall be provided with a brake g²⁰, the latter will be moved into engagement with the block F' when the lever g⁶ is pressed

in, as just described, by the hand of the operator.

The gear-wheel g² engages with a gear-wheel g¹¹, affixed to a shaft G², supported in 70 bearings g¹². The gear-wheel g¹¹ engages with the gear-wheel g¹³, that is affixed to a shaft H, that is journaled in a bearing h. Affixed to the upper end of this shaft H is a beveled gear-wheel h', that meshes with a beveled gear-wheel h², affixed to the shaft C⁷. Thus it will be seen that the motion is transmitted from the shaft C⁷ for the rotation of the reels F. 75

The reels F each have a head, to the outer 80 portion of which are pivoted by pins f' a number of arms f². As here shown, there are four of these arms f². Their lower extremities are turned outwardly to form supports f³. Between their ends these arms f² are pivotally connected by pins f⁴ with the outer ends of links f⁵, whose inner ends are pivotally connected by pins f⁶ with a socket f⁷, that is connected with the head f of the reel F by means of a tube f⁸, forming a central stem. 85 90

Below the head f the tube f⁸ is provided with a collar or circular projection f⁹, and at the upper end the tube is adapted to slide longitudinally through the head f. Above the head a suspending-eye f¹⁰ is connected 95 with the tube f⁸, so as to swivel upon the same. At the lower end this swivel-eye has lugs f¹¹, which when the swivel-eye occupies its normal position are under hook-shaped lugs f¹², with which the head f is provided. 100 When the lugs f¹¹ of the swivel-eye are thus engaged with the lugs f¹² of the head f, the tube f⁸ will be incapable of sliding longitudinally through the head f. A locking-piece f¹³, pivotally connected by a pin f¹⁴ to one of 105 the lugs f¹² of the head f, serves to prevent the disengagement of the lugs f¹¹ from the lugs f¹².

By a rotary movement of the swivel-eye in one direction a rotary movement in the other direction is precluded by reason of having an abutment in the lugs f¹² for the ends of the lugs f¹¹. This abutment may be formed by simply inclining the outer ends of the lugs f¹¹ and correspondingly shaping the opposite 110 surfaces of the lugs f¹². If this locking-piece f¹³ be swung to one side, it will become possible to swivel the eye f¹⁰ so as to disengage its lugs f¹¹ from the lugs f¹² of the head f. Then the tube f⁸ may be slid upwardly 115 through the head f. The raising of the socket f⁷ incident to this sliding motion of the tube f⁸ will draw the links f⁵ inward, and thus the lower ends of the arms f² will be moved toward each other. The reel will thus be 120 collapsed, so that the wire may be disengaged from it. Indeed, the coil of wire will ordinarily drop off as soon as the reel is collapsed. During the winding operation a reel F is 125 engaged with a block F', so as to rotate with the latter, and hence with the shaft G, and wind the drawn wire upon itself. 130

In the circumference of the block F' are a number of vertical grooves corresponding to the number of arms f² in the reel, and when the reel is in place its arms engage with these 5 grooves. The socket f⁷ rests upon the top of a hub with which the block is provided and fits upon the upper extremity of the shaft G.

Preferably a guard-band f¹⁵ extends around the lower part of each block F', and consequently around the lower part of each reel F, to prevent the wire from flying outward away from the reel at the end of winding. After the proper quantity of wire shall have been wound upon the reel it is lifted off by 15 means of its swivel-eye f¹⁰ to make place for another reel.

If a filled reel is to be taken to another place, so that the wire upon it may be drawn still finer, a convenient way of removing it 20 would be to place it upon a carriage I, as shown in Fig. 8. This carriage has a platform i, supported by two pairs of wheels i', the forward pair of which may be swiveled to the platform, if desired. Above the platform i a post i² extends upward. A table i³ is supported by the post i² in such a manner as to be free to swivel or rotate about the same. In its upper surface are recesses i⁴ for the reception of the supports f³, formed at 25 the lower extremities of the reel-arms f². Obviously this table i³ may rotate for unwinding a coil of wire upon a reel F, which is supported upon the post i².

It would be advantageous to use two reels 30 in connection with each of the series of rollers and drawing-dies and to alternate these two reels in the position for taking wire. To facilitate the alternation of the reels, I combine them with a bar J. As here shown, this bar 40 J is supported by a turn-table J', (shown best in Fig. 9,) comprising a center bolt j, through the lower end of which the bar J passes. The upper end of the center bolt j has a head j', that rests above a plate j². A corresponding 45 plate j³ surrounds the lower part of the center bolt j below a shoulder j⁴, with which the said bolt is provided. Beneath the plate j³ is a washer j⁵. Beneath this washer a key j⁶ passes through that slot in the center bolt 50 through which the bar J passes, the key being longitudinally inclined and serving to effect the clamping of said bar J in the center bolt. Between the plates j² and j³ are plates j⁷ and j⁸, which are affixed to bars K, forming 55 part of an elevator. Between the plates j² and j³ and also between the plates j³ and j⁸ are antifriction-rollers j⁹. Obviously the plates j² and j³, together with the center bolt j, may rotate relatively to the plates j⁷ and j⁸. By this means the 60 bar J may be oscillated about the center bolt j as an axis of motion. Each bar J has at its end hooks j¹⁰. These hooks may be swiveled in stirrups j¹¹, which are pivotally connected by pins j¹² with the ends of the bar J. As 65 shown in Fig. 10, each hook j¹⁰ may have a swiveling connection with a hanger provided

with a peripherically-grooved roller r, adapted to travel along the upper edge of the bar J.

The elevator-bars K are attached to the plunger k of a hydraulic engine K', that is controlled by any suitable valve and, as here shown, through the agency of a wheel k² and an adjustable rope k³, which is applied to the said wheel k² and extended around the guide-pulleys k⁴ k⁵ to positions where it will 75 be convenient of access.

A table L is arranged in convenient relation to each of the blocks F'. As here shown, it is supported by a post l, extending from the floor. In its upper surface are recesses 80 l' for the supports f³ of a reel. This table may be precisely like the table i³ heretofore described in connection with the carriage I. A swiveling connection is formed between each table L and each post l by means of a 85 center screw l² or in any other convenient way. Each table has a number of radial notches l³ extending inward from its circumference. Reference to Fig. 1 will show that the approved arrangement is one wherein the 90 center of a block F', the center of a turn-table J', and the center of a table L will be intersected by one straight line. When the parts are thus arranged, the adjustment of a bar J into such position that one of its hooks 95 j¹⁰ will engage with a reel F which is taking wire will cause the other hook j¹⁰ of said bar J to occupy a position over the table L. Hence two reels may be engaged with one bar J at the same time.

Whenever a reel has been filled with wire, the bar J will be swung around and lowered, so that one of its hooks j¹⁰ may be engaged with the swivel-eye j¹⁰ of that reel. At the same time the other hook j¹⁰ of said bar J will 100 be engaged with a reel resting upon the corresponding table L. Then the elevator will be raised, and afterward by hand the bar J will be turned, so as to transpose the two reels, the filled reel being thus deposited upon the 105 table L and the empty reel being deposited upon the block F', ready to take wire from the adjacent series of rollers and drawing-dies. The wire upon the reel deposited on the table L may now be prepared for removal by inserting wires or cords through the notches l³ of the table L up into the inside of the coil of wire in order that it may be bound to preserve it in coil form. Afterward the reel may 110 be collapsed by swinging aside the catch j¹³ and engaging one of the hooks of the bar J 115 and elevating the reel by means of the elevator. The elevator may be counterbalanced. I have shown a counterbalance-cable k⁶, which is intended to lead to a weight conveniently 120 located.

By reason of the clutch G', which, as will have already been understood, is a friction-clutch, I can start and stop the reel holder or block F' at pleasure and do so gradually, 125 while the rollers C' to C⁶ are left running. When it is started, it will tighten the coil of

wire upon the roller C⁶ and cause that to draw the wire forward. This will have the effect of tightening the wire upon the roller C⁵, and so one roller after the other will be caused to act upon the wire to draw it forward. Whenever the reel holder or block is stopped, the loops of wire surrounding the rollers will become slack and the wire will no longer be moved forward by the rollers.

10 I desire to cover a means at any suitable part of the machine for starting the block with a graduated movement and without stopping the driving-shaft, as in this way it will be possible to operate at a higher speed than otherwise could be done.

15 The combination of parts for changing reels, including the hydraulic elevator, facilitates the drawing of wire rapidly, and therefore conduces to the main object of my invention.

20 What I claim as my invention, and desire to secure by Letters Patent, is—

1. In a wire-drawing machine, the combination of a die, a rotatable drawing-block, a drawing-roll, means for rotating the said drawing-roll, a starting and stopping mechanism for starting the drawing-block with a graduated movement, and means for throwing said starting and stopping mechanism into and out of action without stopping the drawing-30 roll, substantially as described.

2. In a wire-drawing machine, the combination of a die, a drawing-block, a driving-shaft, a continuously-rotating drawing-roll operated from said driving-shaft, a starting-35 and stopping mechanism between the driving-shaft and drawing-block for starting the block with a graduated movement, and means for throwing into and out of action said starting and stopping mechanism, without stopping and the driving-shaft, substantially as described.

3. In a wire-drawing machine, the combination of a die, a rotatable drawing-block, a drawing-roll, means for rotating the drawing-roll, a friction-clutch for starting the block 40 with a graduated movement and means for throwing said clutch into and out of action without stopping the drawing-roll, substantially as described.

4. In a wire-drawing machine, the combination of a series of dies, continuously-rotating drawing-rolls, intermediate said dies, a drawing-block, a driving-shaft for operating said drawing-rolls and drawing-block, a starting-45 and stopping mechanism between said block and driving-shaft for starting the drawing-block with a graduated movement and means for throwing said starting and stopping mechanism into and out of action without stopping the driving-shaft, substantially 50 as described.

5. In a wire-drawing machine, the combination of a series of dies, a rotatable drawing-block, drawing-rolls, means for positively rotating said drawing-rolls, a starting and stopping mechanism for starting the drawing-block with a graduated movement and means for throwing into and out of action said start-55

ing and stopping mechanism without stopping the drawing-rolls, substantially as described.

6. In a wire-drawing machine, the combination of a series of dies, a rotatable drawing-block, drawing-rolls, means for positively and uniformly rotating said rolls, a starting and stopping mechanism for starting the drawing-block with a graduated movement, and means for throwing into and out of action said starting and stopping mechanism without stopping the drawing-rolls, substantially as described.

7. In a wire-drawing machine, the combination of a series of dies, a rotatable drawing-block, drawing-rolls, means for positively, uniformly and continuously rotating said rolls, a starting and stopping mechanism for starting the drawing-block with a graduated movement, and means for throwing into and out of action said starting and stopping mechanism without stopping the rolls, substantially as described.

8. In a wire-drawing machine, the combination of a die, a drawing-block, means for operating said block, a starting and stopping mechanism comprised in said operating means for starting the block with a graduated movement, means for throwing said starting and stopping mechanism into and out of action, and a brake for said block adapted to be operated when the said starting and stopping mechanism is thrown out of action, substantially as described.

9. The method of stringing a wire-drawing machine which has in combination a series of die-holders, continuously-rotating drawing-rolls intermediate the die-holders and a drawing-block in advance of the forward die-holder, said method consisting in stringing a wire with spaced dies that fit in said holders, coiling the wire about each roll in a loop longer than is sufficient to tightly embrace the roll and placing the intermediate dies in the holders, so that not until the block is started and the drawing operation begins through the forward die will the loops be successively tightened to enable the rolls to operate upon them to draw the wire through the successive dies, a gradual action of the rolls upon the wire being thus effected and wearing and heating of the wire being thus prevented.

10. The method of stringing a wire-drawing machine having in combination a series of die-holders, dies fitting in said holders and capable of movement forward and backward in the line of movement of a wire, continuously-rotating drawing-rolls intermediate the die-holders and a block in advance of the forward die-holder, said method consisting in stringing a wire with the dies and coiling the wire about each roll in a loop longer than is sufficient to tightly embrace the roll, so that as the block is started the drawing operation will begin through the forward die, and the loops will be successively tightened to enable

- the rolls to operate upon the wire to draw it through the successive die, a gradual action of the rolls upon the wire being effected, and wearing and heating of the wire being thus prevented.
11. The method of stringing a wire-drawing machine which has in combination a series of die-holders, continuously-rotating drawing-rolls intermediate the die-holders, a drawing-block in advance of the forward die-holder, and means for starting the block with a graduated movement, said method consisting in coiling a wire, carrying dies that fit in said holders, about each roll in a loop longer than is sufficient to tightly embrace the roll, so that as the block is started and the drawing operation begins, through the forward die, the loops will be successively tightened to enable the rolls to operate upon the wire to draw it through the successive dies, a gradual action of the rollers upon the wire being thus effected and wearing and heating of the wire being thus prevented, substantially as described.
12. In a wire-drawing machine, the combination of a series of dies supported so as to be capable of movement forward and backward in the line of movement of the wire, continuously-rotating drawing-rolls intermediate the dies, a block in advance of the forward die, means for starting the block with a graduated movement, and the wire, on which the dies are strung, coiled about each roll, said dies being adapted to have a rearward movement therein in the direction of the length of the wire when the drawing-block is stopped from operating, so that the coil of wire about each drawing-roll will be loosened about the roll, substantially as described.
13. In a wire-drawing machine, the combination with sliding die-holders, dies in such holders, a roller intermediate the die-holders, and a block in advance of the forward die-holder, whereby upon the stoppage of the block and the reverse movement thereof the adjacent die may move to enlarge the loop around the roller, substantially as specified.
14. The combination with a device for moving wire through a die, of a longitudinally-sliding die-holder with which the said die is loosely engaged in the direction of the length of the wire, so that when the drawing of the wire is stopped the die may move backward in the die-holder, substantially as specified.
15. The combination with a device for moving wire through a die, of a die-holder, having an opening below the die and a die supported above said opening so that after the wire has been drawn through the die, the die may drop through the opening, substantially as specified.
16. A drawing-roller for a wire-drawing machine having a hollow flange formed with openings, said roller being provided with passages in communication with said hollow flange through which liquid circulates, substantially as described.
17. A drawing-roller for a wire-drawing machine having a flange provided with passages for the circulation of liquid, substantially as specified.
18. In a wire-drawing machine, the combination of a drawing-roller having its body provided with passages for liquid, a stationary head having passages for liquid communicating with the body of the roller, and means for supplying liquid to the stationary head, substantially as specified.
19. In a wire-drawing machine, the combination of a drawing-roller having its body provided with passages, a stationary head arranged in such relation with the body of the roller that a liquid-passage will be left between them, and means for supplying liquid to the stationary head, substantially as specified.
20. In a wire-drawing machine, the combination of a drawing-roller having its body provided with liquid-passages, a hollow flange for receiving liquid having passages which lead to the inside and outside of the body of the roller, and a stationary head provided with passages leading to the inside and to the outside of the body of the roller, substantially as specified.
21. In a wire-drawing machine, the combination with a drawing-roller around which liquid is circulated, of a sliding shield for limiting the throw of liquid from the roller, and means in connection with said shield for holding it in an elevated position above the roller, substantially as described.
22. In a wire-drawing machine the combination with a drawing-roller around which liquid is circulated, of a shield for limiting the throw of liquid from the roller, and means whereby the said shield may be supported in different relations to the roller, substantially as specified.
23. In a wire-drawing machine, the combination with a drawing-roller upon the outside of which liquid is circulated and a die-holder adjacent to said roller, of a shield against which liquid will be thrown from the outside of the roller, and an extension on said shield by which the liquid will be deflected into the die-holder, substantially as described.
24. In a wire-drawing machine, the combination with a block, of a reel the arms of which are adapted to be fitted to the same and to be removed therefrom without collapsing, and means in connection with said arms for collapsing them, substantially as described.
25. In a reel, the combination of a head, of a central stem adapted to slide in said head, arms pivoted at one end to the head, and links pivoted at one end to the arms intermediate their length and at their other end to the central stem, substantially as described.
26. In a reel, the combination of a head, arms pivotally connected to the head, links pivotally connected to the arms, a stem pivotally connected to the links, having a sliding bearing in the center of the head, a swivel-

- eye connected to the stem, and means for engaging the swivel-eye so as to prevent the movement of the stem relatively to the head, substantially as specified.
- 5 27. In a reel, the combination of a head, arms pivotally connected to the head, links pivotally connected to the arms, a tubular stem pivotally connected to the links, adapted to be fitted upon a support, and having a 10 sliding bearing in the center of the head, and means for locking the said stem and head together, substantially as specified.
- 15 28. In a reel, the combination of a head, arms pivotally connected with the head, links 15 pivotally connected to the arms, a stem pivotally connected to the links, and having a sliding connection with the head, a swivel-eye connected with the stem, lugs upon the 20 swivel-eye and upon the head and a catch for holding the lugs of the swivel-eye and of the head in engagement, substantially as specified.
- 25 29. The combination of a drawing-block carrying a reel which is rotated therewith, an elevator carrying a turn-table, arms extending from said turn-table, one of said arms adapted to be connected with the reel rotated by the block, while the other of said arms is adapted to be connected with the second reel, 30 substantially as described.
- 30 30. In a wire-drawing machine, the combination of an elevator, a support for two reels pivotally connected with a part of the eleva-
- tor and reels supported so as to be able to rotate relatively to said support, substantially 35 as specified.
31. In a wire-drawing machine the combination of an elevator, a support for two reels pivotally connected with a part of the elevator, and reels supported so as to be able to 40 swing relatively to said support, substantially as specified.
32. In a wire-drawing machine the combination of an elevator, a support for two reels pivotally connected with a part of the elevator, and reels supported so as to be able to 45 travel along said support toward and from its pivotal connection.
33. In a wire-drawing machine, the combination of a die, a drawing-block, a driving-shaft, means for rotating said shaft at a high speed, a device for starting the block with a gradual movement to obtain the full speed of the driving-shaft and means including a handle independent of the driving-shaft, for 50 throwing said device into and out of action without stopping the driving-shaft, substantially as described.
- 55 In testimony whereof I have signed my name to this specification in the presence of 60 two subscribing witnesses.

CHARLES A. COWLES.

Witnesses:

ANTHONY GREF,
F. ROBERTS.
